UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING APPARATUS.

Application filed March 14, 1922. Serial No. 543,659.

This invention pertains to improvements in lubricating apparatus. It is among the objects of the invention to provide a simple and efficient system and apparatus of the type wherein a single source of lubricant under pressure may be connected to and disconnected from a plurality of lubricant-receiving parts.

In the drawings, which show a preferred form of one illustrative embodiment of my invention:

Figure 1 is a side elevation of a lubricant-expelling device;

Fig. 2 is a central longitudinal section through the nozzle of said device, being partly in elevation, and showing the relation of the parts pursuant to introduction of the nozzle over the lubricant-receiving element but prior to initiation of the coupling operation;

Fig. 3 is a section partly in elevation and similar to Fig. 2 except that it shows the relation of the parts pursuant to coupling and valve-opening operation;

Fig. 4 is a side elevation of the nozzle with the rear end thereof removed;

Fig. 5 is an end elevation of the nozzle with the lubricant-receiving element entered therein;

Fig. 6 is a section on the line 6-6 of Fig. 2;

Fig. 7 is a section on the line 7-7 of Fig. 2;

Fig. 8 includes a side elevation, a central longitudinal section and rear end elevation of a preferred form of sealing part or gasket holder which also serves as a valve part; and

Fig. 9 includes a side elevation, a central longitudinal section and rear elevation of a preferred form of valve part cooperating with the gasket holder or valve part shown in Fig. 8.

Referring to the drawings and to the preferred form of my invention selected for illustrative purposes, I have shown a lubricant-expelling device herein shown as of the so-called "gun" type including a barrel 10, rear head 11 into which is screw-threaded a stem 12 carrying the usual lubricant-expelling plunger or piston, not shown, at its inner end and provided at its outer end with a handle 13. At the discharge end of the

gun, I have shown a front head 14 presenting or cooperating with a nozzle including a valved coupling. This valved coupling may include a coupling sleeve 15, connecting sleeve, gasket holder or sealing part 17 carrying the gasket 18 serving as a valve part in cooperation with a valve part 19. The preferred form of coupling illustrated is of the rotary type, there being preferably no longitudinal movement of the gasket holder 17 relative to the coupling sleeve 15. A tight seal may be provided by the lubricant-pressed washer 18, which is preferably adapted to be pressed toward the lubricant-receiving end of the lubricant-receiving nipple 20 by a slideable piston or gasket 21, which may be of leather or the like, and which may be interiorly supported by a spring cup 22. The lubricant-receiving nipple 20 is preferably, as illustrated, of the type shown in my copending application, Serial No. 543,654, filed herewith, and presenting a part 23 generally triangular in cross-section and providing three projections adapted to overlie flange portions 24 of the coupling sleeve 15 when the latter is passed thereover and turned relative thereto. The connecting sleeve 16 has a triangular aperture therethrough corresponding to the cross-section of the triangular portion 23 of the nipple 20 and to the adjacent end of the gasket holder 17 over which the connecting sleeve 16 passes to prevent rotation of the gasket holder relative to the nipple when the latter is entered in the nozzle. Adjacent the lubricant-receiving end of the nipple, I may provide a generally cylindrical extension 25 preferably undercut, as illustrated. The lubricant-receiving nipple may be drilled its entire length and provide a seat for a ball check at one end and for a spring urging said ball check into closed position at the opposite end. The sleeve 16 prevents relative turning movement between the lubricant-receiving nipple 20 and the gasket holder or sealing part 17. The sleeve 15 may turn relative to these parts through a number of degrees determined by the limiting slot and pin 26, 27, best shown in Fig. 4.

The valve part 19 is held against rotation relative to the coupling sleeve 15 by a pin 30, which may be entered in a slot 31 in the

2

valve part 19 to permit slight longitudinal movement of the valve part relative to the gasket holder 17 so that a tight seal may be presented between the abutting surfaces of these parts. The gasket holder or sealing part 17 may be provided with a port 32 and the valve part 19 may be provided with a port 33, these parts being brought into register when the coupling sleeve 15 has been turned relative to the gasket holder 17 and to the relative position illustrated in Fig. 4 where the coupling operation is complete. Lubricant passing through the ports 33 and 32 will press against the piston 21 and urge the gasket 18 into sealed relation to the head of the nipple. On closure of the valve by bringing the ports 32 and 33 out of register, this pressure may relieve itself by lubricant passing into or through the lubricant-receiving nipple 20. It will be observed that no relative turning movement between the gasket 18 and nipple 20 takes place either during the coupling or uncoupling operation. The coupling sleeve 15 may be screwed into or otherwise rigidly secured to the head 14, while leakage to this joint or to the joint between the rear end of the coupling sleeve 15 and valve part 19 may be prevented by a piston or cup leather 40 having an aperture 41 therethrough registering with a corresponding aperture in the head 14. Lubricant entering the chamber between the cup leather 40 and valve part 19 will tend to force the valve part forward to provide a tight joint with the rear face of the gasket holder 17. To hold the cup leather or piston 40 in tight relationship to the head 14 in the absence of any considerable pressure, a spring 43 may be provided between the cup leather 40 and the valve part 19. The cup leather 40 may be interiorly supported by a spring cup 45.

Assuming the parts of the valved coupling to be in the position illustrated in Fig. 2, the triangular aperture in the connecting sleeve 16 will register with a triangular opening in the end of the coupling sleeve 15 and the nozzle may be slipped over the correspondingly shaped portion 23 of the lubricant-receiving nipple 20. The face of the lubricant-receiving nipple adjacent the check valve will press slightly against the gasket 18 and as the gasket holder or sealing part 17 is held against rotation by the connecting sleeve 16, a turning of the coupling sleeve 15 will bring the projections on the nipple over the end flanges of the coupling sleeve to the position shown in dotted lines in Fig. 5, at which time relative rotation will stop because the pin 27 of the gasket holder will have reached the end of the slot 26 in the coupling sleeve.

At the same time that rotation stops, the ports 32 and 33 of the rotary valve will be in register. Lubricant under pressure will

now pass through the ports 33, 32 and exert sealing pressure on the gasket 18 by reason of their pressure against the piston or cup 21, thus effecting a tight joint. The lubricant under pressure will now open a check valve in the lubricant-receiving nipple and lubricant may be forced therethrough to the desired extent. It will be noted that the coupling and valve opening operation is effected by rotary movement of the gun barrel. The direction of the thread on the stem 12 of the gun is preferably such that rotation in this same direction, preferably clockwise, exerts the lubricant expelling pressure. Therefore the entire coupling, valve opening, sealing and lubricant-expelling operations may be effected in the sequence mentioned by clockwise rotation of the handle 13. Conversely, valve closure, relief of pressure and uncoupling operations may be effected in the order named by opposite preferably counter-clockwise rotation of the handle 13 or of the barrel 10, as may be preferred.

The boring out of the valve part 19 to present the cylindrical recess within which the piston or cup leather 40 works, not only provides a tight seal but also reduces somewhat the area of the valve part 19 which is subjected to the pressure of the lubricant. By this I mean that the pressure of the lubricant is confined to the cross-sectional area of the bore in which the cup leather 40 is located, because the leather 40 prevents any lubricant pressure being exerted upon that portion of the part 19 encircling the leather 40, as shown in Figs. 2 and 3. Thus it will be noted that, as the cross-sectional area of the largest part of the bore of the part 19 is smaller than the cross-sectional area of the part 17, the same aggregate pressure exerted upon the smaller area of the part 19 will be exerted upon the larger area of the part 17 and therefore the pressure per square inch on the part 17 will be less than on the part 19. This cutting down of area is particularly desirable where high pressures of from eighteen hundred to three thousand pounds per square inch are to be exerted on the lubricant.

While I have shown and described a preferred embodiment of my invention, it will be understood that my invention is not limited to the specific embodiment thereof shown and described, but may be considerably varied within the scope of the appended claims.

I claim:

1. Lubricating apparatus comprising a lubricant gun having a discharge nozzle presenting a lubricant-pressed sealing part and a rotary valve cooperating therewith, and a coupling for engagement over a lubricant-receiving nipple presenting coupling projections, said lubricant-pressed sealing part in-

cluding a gasket holder, a gasket for engagement with a face of the lubricant-receiving nipple surrounding a lubricant-receiving aperture therein and a piston carried by said 5 gasket holder and urging said gasket forwardly into sealed relation to said face of the nipple.

2. Lubricating apparatus comprising a source of lubricant under pressure presenting 10 a nozzle for connection to a lubricant-receiving nipple presenting a lubricant-receiving aperture at one end thereof and projections adjacent said end, a sealing part in said nozzle, means for holding said sealing part against rotation relative to the nipple while permitting limited rotative movement 15 of said nozzle, a sealing gasket carried by said sealing part and a reciprocable piston within said sealing part for exerting sealing pressure against said sealing gasket.

3. A lubricant gun presenting at its discharge end a nozzle for a connection with a lubricant-receiving nipple, relatively rotatable valve parts carried by said nozzle, 25 the valve part nearer said gun having an axially bored recess formed therein, and a spring pressed cup washer in said bore and

making sealing contact with the end of said compressor.

4. A lubricating gun presenting at its discharge end a valved coupling having two relatively rotatable valve parts and means for reducing the pressure per square inch between said valve parts below the pressure per square inch exerted on one face of one 25 of said valve parts, said means including a recess in one of said parts and a sealing piston in said recess.

5. A lubricant-expelling device comprising, in combination, a barrel, piston means 40 for expelling lubricant from said barrel, a front or discharge head for said barrel, a coupling or nozzle sleeve rigidly secured to said front head, a sealing part rotatable relative to said nozzle or coupling sleeve, a co-operating valve part non-rotatable relative to said nozzle sleeve but mounted for limited longitudinal movement relative thereto and 45 slideable packing means between said valve part and said head.

In testimony whereof, I have signed my name to this specification.

HOWARD J. MURPHY.
